BAG FEEDING MECHANISM

Edward E. West, Richmond, Va.

Application September 19, 1940, Serial No. 357,458

11 Claims. (Cl. 112—2)

This invention relates to improvements in bag feeding means for stringing machines.

The principal object of the present invention is the provision of improved means for horizontally feeding hemmed bags onto bag positioning and holding means of a bag stringing machine, as described in my Patent No. 2,274,622.

A further object is to provide an improved bag feeding mechanism for accurately and uniformly delivering hemmed bags to a bag positioning and holding means for stringing.

Another object is to provide a bag feeding mechanism having improved hem gripping and opening means for accurately aligning the bags on the bag holding device to assure of the bags being uniformly and properly strung.

These and other objects and advantages will be apparent as the following specification is considered in connection with the accompanying drawings wherein:

Figure 1 is a plan view of the improved bag feeding mechanism;

Figure 2 is a side elevation of the bag feeding mechanism, and the operating means therefor, showing the feeding and gripping carriage in position to receive a hemmed bag;

Figure 3 is an enlarged section through the bag feeding and hem gripping carriage, showing the combined pusher and bag opening fingers in hem entering position, and the side hem grippers in open position;

Figure 4 is an enlarged side view of the side hem grippers in open position;

Figure 5 is a detailed perspective view of the lever and pin for operating the side hem grippers;

Figure 6 is a diagrammatic view of the pusher and bag opening fingers in the position they assume when inserted within the bag hems, and the side hem grippers in open position;

Figure 7 is a diagrammatic view of the pusher and bag opening fingers in the position they assume when inserted within the bag hems, and the side hem grippers clamping the side of the hems;

Figure 8 is a diagrammatic view of the pusher and bag opening fingers in the position they assume when spreading open the mouth of the bag, and the side hem grippers clamping the side of the hems;

Figure 9 is a diagrammatic view of the pusher and bag openings fingers and the side hem grippers in the positions they assume when positioning a hemmed bag on the supporting arms;

Figure 10 is a cross section through a portion of a hemmed bag in the position it assumes after

being finally arranged on and engaged by a pair of bag holding arms; and

Figure 11 is a diagrammatic view of the directional movements of the carriage rock shaft for actuating the pusher and bag opening fingers and the side hem grippers.

Generally considered, hemmed bags are delivered, in chain connected form from a source of supply, to a horizontally disposed feeding and cutting mechanism which engages the hems of the successively fed bags, severs the connecting seam threads, and carries successive bags onto one horizontally disposed pair, of four radially extending pairs of bag holding arms of a rotating turret head. The bags are thereafter adapted to be operated upon by a stringing mechanism, which does not constitute a part of the present invention.

Referring more particularly to the drawings, wherein like reference characters designate similar parts throughout the several views, the numeral 1 denotes a drum upon which a source of hemmed bag supply, in the form of a roll 1' is carried. The drum 1 is rotatably supported on the rear ends of a pair of rearwardly extending brackets 2 secured by bolts, or the like 3 to the rear wall 4 of the main machine frame 5, of a stringing and tagging machine 6, only a portion of which is shown. The roll of chain-thread-connected, hemmed bag lengths 7 are wound on the drum 1 and, as the roll is rotated, in a manner presently described, the connected bag lengths are delivered over an idler roller or the like 8, suitably mounted on the rear wall 4 of frame 5. A substantially flat, rectangular feed or transfer plate 9 is rigidly supported by L-shaped brackets 10, suitably secured to a side wall 11 of the main frame 5. A pair of spaced, longitudinally extending, bag guide runners 12, suitably secured by screws or the like 13 to the top face of the plate 9, cooperate with the plate to provide a guide or runway along which the bag lengths 7 are fed, in chain fashion, from the roll 1'. A pair of downwardly and forwardly extending, substantially flat, spaced, spring fingers 14, secured at their rear ends to the runners 12, rest lightly upon the top surfaces of the bag lengths 7 and serve to retain the same in proper alignment, as the bag lengths are fed along the guide plate 9, between the runners 12.

The roll 1' of chain-connected bag blanks 7 rests upon and is rotated by a friction roller 80, carried by a shaft 81 journalled in the rear or lower end of a rearwardly extending bracket 82. The upper or front end of bracket 82 is loosely

or pivotally connected to a shaft 83, journalled in a boss 84 mounted on the rear wall 4 of the machine frame 5. A disk 85, mounted on the outer end of shaft 83, frictionally engages with the side face of and is rotated by a sprocket wheel 86, mounted on a main longitudinal drive shaft 25 suitably journalled in the machine frame and driven by a source of power, not shown. Pulleys or sheaves 87-87' mounted on the shafts 84 and 83, respectively, are connected by a flexible belt 10 or the like 88, so that rotation of the main drive shaft 25 in turn rotates the roller 89, through the medium of disk 85 and belt 88, and the roller 89 in turn frictionally engages and rotates the roll 1' to deliver the chain-connected bag blanks 7 to the feed or transfer plate 9. By adjusting the disk 85, relative to the sprocket wheel 86, the rate of rotation of the roller 89 may be varied to increase or decrease the rate of delivery of bag blanks 7 to the feed plate 9. Thus, a rod 107, rotatably mounted in the machine frame 5, is formed with a threaded inner end 108 which threadedly engages a boss 109 sleeved on the shaft 83, adjacent the disk 85, and held in position thereon by a collar 110. As the pulley 87' is keyed on the shaft 83, as at 111, rotation of the rod 107, in the appropriate directions, by means of hand wheel 112, slides the shaft 83 through its boss 84 and pulley 87', and moves the disk 85 toward or away from the center of the sprocket wheel 86. This adjustment of the rod 107 and disk 85 increases or decreases the speed of rotation of the disk 85 and controls the rotation of the pulleys 87 and roller 89, in an obvious manner.

In order to compensate for the gradual decrease in the diameter of roll 1, as bag lengths are unrolled therefrom, and to prevent the roller 89 from breaking its frictional engagement therewith, I provide means for automatically elevating the roller 89. Thus, a pulley or sheave 89 is suitably journalled on the end of one of the roll supporting bracket arms 2. A cable or wire 90, attached at its upper end to an arm 90' secured to bracket 82, passes over the pulley 89 and has a suitable weight 91 connected to the lower end thereof. This weight 91 exerts a constant upward pull on the cable 90, arm 90', swinging or rocking the bracket 82 about the shaft 83 as a pivot, and causes the roller 89 to be continuously elevated into frictional engagement with the roll of bag lengths as the latter unwind during the feeding of the bag blanks 7 to the feed or transfer plate 9.

A bag pusher member, comprising a downwardly and forwardly extending, relatively flat, resilient plate or tongue 15, is secured by a bolt 16, to the outer ends of a pair of laterally extending rods 17, substantially intermediate the bag guide runners 12. The rods 17 are mounted in and project through a vertically disposed block 18, slidably arranged in a slot or guide track 19 in the side frame wall 11. A vertical lever 20 is pivotally connected, at its upper end, to an arm 23 (see Figure 1), in turn pivoted to the side of the block 18, with the lower end of the lever being fulcrumed to a bracket 20' on the machine frame. A roller 21, mounted on the lever 20, intermediate the ends thereof rides in a cam groove 22 in the face of a cam disk 53, mounted on the horizontal drive shaft 24. The shaft 24 is provided with a gear 24', which meshes with a worm 24'', as shown in Figure 2, on the main longitudinal drive shaft 25. During rotation of the cam 53, the lever 20 is rocked and the block 18 is reciprocated in the guide track 19 whereby the spring bag 75

pusher plate 15 is likewise moved forwardly and rearwardly on the feed or transfer plate 9. The forward edge of the spring plate 15 is adapted to extend into or underneath the top hem 26 of the hems 1' of the foremost bag blank 7, of the chain of bags, and advance the bags intermittently beneath a pair of cutters 27.

The bag cutters 27, of substantially L-shape, extend upwardly and are vertically movable through guide slots 28, in the feed plate 9, adjacent the forward ends of the bag guide runners 12, and are pivotally connected to the forward ends of a pair of rods 29. These rods are fixed at their rear ends to a rock shaft 30, in turn journalled in suitable blocks 31, secured to the underside of plate 9. The cutters 27 are provided with suitable cutting edges, not shown, so that when the rock shaft 30 and rods 29 are rocked downwardly, as presently described, the cutters 27 are likewise moved downwardly through the guide slots 28 until their respective cutting edges coact with cutting edges, 28', on the upper ends of the slots 28 and thereby shear or sever the connecting bag threads. Two coil springs 33 on the forward ends of the rods 29 engage the faces of the blades 27 and maintain the cutters in vertical alignment with respect to the slots 28 thereby assuring of an accurate cutting or shearing contact between the respective cutting edges.

The rock shaft 30 extends through an opening 30 in the side wall of the machine frame and a small cam lug 34 is fixed on the inner end thereof. The lug 34 carries a tension spring, not shown, which is compressed against the underside of the feed plate 9, when the rock shaft 30 and cutters are rocked or moved downwardly to perform the cutting action, and serves to return the cutters to their normal elevated position after the cutting operation has been performed. A spring tensioned trip finger 35, pivotally connected to the side of the sliding block 18, is adapted to slip or slide freely over the upper end of the rock shaft cam lug 34, during the rearward travel of the block. On the forward travel of block 18, the trip finger 35 engages with the cam lug 34 and rotates the same so that the rock shaft 30 and rods 29 are rocked downwardly, in a clockwise direction, viewing Figure 2, and the cutters 27 are moved downwardly through the slots 28 to sever the connecting bag threads. After the cutters, on their downward movement through slots 28, have severed the connecting threads, the spring, not shown, causes the rods 29 and cutters 27 to return to their normal elevated position, in substantially the same manner as described and illustrated in my copending application Serial No. 250,223, filed January 10, 1939. It should be noted that the bag pusher plate 15 engages or enters the top hem 26 of the bag 1 while the latter is stationary with the hem slightly to the rear of the thread cutters 27, and that the cutting of the threads occurs as the bag is in motion, that is being pushed forwardly.

The bags, after having their connecting threads severed, are advanced or pushed along the feeding plate 9, by the bag pusher plate 15, into position to be gripped by a reciprocating bag gripper and feed carriage 36. At the end of its forward stroke, the pusher plate 15 stops and holds the hemmed bag stationary until the feed carriage 36 is moved rearwardly and reaches a hem gripping position. In other words, the pusher plate 15 remains in the top bag hem 26 and properly aligns the bag until the feed carriage 36 is in position to permit of the bag being gripped. This carriage comprises a

pair of guide rods 37 slidably extending through suitable blocks 38 on the underside of feeding plate 9. A pair of uprights 39 are secured to the forward ends of the guide rods 37, and a pair of parallel, spaced, top rock shafts 40-41, and a pair of parallel, spaced, bottom rock shafts 42-43 extend transversely between and are mounted in the uprights 39. An extended reduced portion 44, suitably secured to the underside of the feed plate 9 at the forward end thereof, is cut away to form two, relatively short, integral bag supporting fingers 45, to permit of the carriage 36 moving close to the forward end of the plate 9.

The bag gripper carriage 36 and the guide rods 37 are reciprocated, relative to the stationary feed plate 9, by means of an arm 46 pivoted at one end to a cross bar 41, fixed to the guide rod 37, and at its other end pivoted to the upper end of a vertical lever 48. The lower end of lever 48 is fixed to a horizontal stub shaft 49 rotatably mounted in a bearing 50, in the main machine frame 5. A lever 51 connected to the outer end of stub shaft 49 carries a roller 52 which rides in a cam groove 54 in the face of the cam 53, mounted on the horizontal drive shaft 24. Rotation of the cam 53 actuates the lever 48 and reciprocates the bag gripper carriage 36 into position to grip the bag and deliver the same forwardly onto a pair of bag holding arms, hereinafter referred to.

A pair of combined pusher and bag opening fingers 55 are sleeved on the front top and bottom rock shafts 40 and 42, between fixed collars 60, thereon and intermediate the ends of the rock shafts (see Fig. 1). Formed on the sleeve portions 61, of the fingers 55, are a pair of vertically and forwardly extending pins 62 having their upper ends bent laterally, as at 64, and frictionally engaging the side faces 66 of a pair of vertically disposed clutch plates 65, integrally formed on one pair of the fixed collars 60 of shafts 40 and 42, for a purpose presently to be described. A pair of vertically and rearwardly extending pins 63, best shown in Figure 3, are also formed on the sleeve portions 61 and are adapted to engage with depending stop screws 58 carried by substantially L-shaped lugs 59, fixed to the rearwardly disposed pair of top and bottom rock shafts 41 and 43, and serve to limit the frictional movement of the pins 62 relative to the clutch plate 65.

Integrally formed on a pair of segment gears 57, sleeved on one end of the top and bottom front rock shafts 40 and 42 are a pair of side hem gripping jaws 56. The bottom segment gear 57 is provided with an integral, rearwardly extending, cam faced or beveled pin 67 which is adapted to engage with a downwardly depending lug 68, fixed to the top rear rock shaft 41, as best shown in Figure 4. A coil or other suitable spring 95, having its upper end fixed to the top segment gear 57 of the upper side hem gripping jaw 56 by a screw 96, and its lower end partially coiled around the rock shaft 41, as at 97, adjacent the lug 68, serves to hold the upper side hem gripping jaw 56 under spring tension, for a purpose hereinafter described. A substantially U-shaped bent lug 69, fixed to the extended outer end of the front top rock shaft 40, is provided with two relatively small, laterally projecting pins 70 which engage with a rearwardly extending lug 71, fixed on the extended outer end of the rear top rock shaft 41, as illustrated in Figure 5.

Integrally formed on a segment gear 92, fixedly secured to one of the extended ends of the top

front rock shaft 40, is a forwardly and vertically extending arm 72. The segment gear 92 meshes with a segment gear 93 fixed to the bottom front rock shaft 42, as best shown in dotted lines of Figures 3 and 4.

A roller 73, rotatably mounted in the outer end of arm 72, is slidably positioned in a longitudinal slot or groove 75' in a cam track or plate 75. The track, as shown in Figure 2, is fixedly secured to and supported upon the upper end of a vertical lever 76, pivotally connected, intermediate its ends, to one end of an arm 77, as at 77', the other end of the arm 77 in turn fulcrumed to the side wall 11 of the main frame 5, as at 77''. The lower extremity of the lever 76 is pivoted to one end of an arm 78', as at 78'', the other end of the arm in turn fulcrumed to the side wall 11 of the main frame 5 as at 78'''. A cam roller 78, carried by the lower end of the arm 76', rides in a cam groove 79 in the face of the cam disk 53, on horizontal shaft 24. Rotation of the cam disk 53 reciprocates the bag gripper and feed carriage 36, relative to the feed plate 9, through the medium of lever 48, and simultaneously elevates and lowers the cam track 75, so that during the movement of the track the roller 73 on arm 72 is free to move within the longitudinal slot 75', and the arm 72 is raised and lowered whereby the top and bottom front rock shafts 40 and 42 are rocked to actuate the pusher and bag opening fingers 55 and the side hem gripper jaws 56, in the following manner.

The bag pushing and opening fingers 55, which as previously described are loosely sleeved on the top and bottom front rock shafts 40 and 42, are moved to open and closed bag hem gripping position, when the shafts 40 and 42 are rocked, by virtue of the frictional engagement between the vertical pins 62, on the sleeve portions 61 of the fingers, and the side faces 66 of the vertically disposed clutch plates 65, carried by these shafts. Thus, when the bag gripper and feed carriage 36 is moved rearwardly to the end of its return stroke, or Figure 2 position, that is, adjacent the forward end of feed plate 9, and the cam track 75 is in raised or elevated position, the combined pusher and bag opening fingers 55 and side hem gripping jaws 56 are in expanded or opened position. Therefore, the forwardly travelling bag pusher plate 15 will push a hemmed bag blank 7 forwardly therebetween so that the hems 7' of the bag blank are positioned ahead of or in front of the fingers 55. Rotation of the cam 53, in a clockwise direction, viewing Figure 2, acts on the vertical lever 76 and depresses or lowers the cam track slightly, in the direction of the arrow 99 Figure 11, so that the fingers 55 are moved to partially closed hem entering position, as shown in Figure 2. The vertical lever 48 is then moved by the continued rotation of cam 53 to swing the bag gripper and feed carriage 36 forwardly a relatively short distance, in the direction of arrow 100, Figure 11, and to move the partially closed fingers 55 into or underneath the top and bottom bag hems 7', whereupon the lever 76 and cam track is depressed or lowered slightly, in the direction of arrow 101, Figure 11, whereby the arm 72 is rocked downwardly, in a counter-clockwise direction. This movement of the arm 72 rocks the top and bottom front rock shafts 40 and 42, through the gears 92-93, in opposing directions, that is counter-clockwise and clockwise, respectively, so that the fingers 55 are moved to their final closed hem gripping position, as shown in Figure 6. As the pusher

and bag opening fingers 55 are inserted within and grip the top and bottom hems 7', the fingers have reached the end of their respective downward and upward movements, with the pins 63 on the finger sleeve portions 61 abutting the stop screws 58 and being limited against further upward movement as particularly shown in Figure 3, so that the clutch plates 65 continue to move relative to the pins 62 during the further rocking movement of the shafts 40 and 42. In other words, by virtue of the frictional engagement between the pins 62 and clutch plates 65, the shafts 40 and 42 may be further rotated or rocked without disturbing the closed pushing and bag opening fingers 55. The lever 76 and cam track 75 continue to move downwardly a slight distance, in the direction of arrow 101 Figure 11, due to the rotation of cam 53, whereby as the bag gripper and feed carriage 36 moves forwardly, the shafts 40 and 42 are further rocked, in counterclockwise and clockwise directions, respectively, which causes the bottom pin 78, on bent lug 68 formed on the end of top front rock shaft 40, to be rocked upwardly into engagement with the rearwardly extending lug 71, fixed on top rear rock shaft 41. The lug 71 is thus swung upwardly which movement rocks the top rear rock shaft 41 in a counterclockwise direction so that the downwardly depending lug 68, on the end of shaft 41, is swung downwardly and rearwardly, in an arc, into engagement with and caused to depress the outer or rear end of the rearwardly extending pin 67, on the bottom side hem gripper segment gear 57, Figure 4. The bottom segment gear 57 is thereby rocked in a clockwise direction and in turn rocks the top segment gear 57, in an opposing or counterclockwise direction, against the tension of leaf spring 88, whereby the side hem gripper jaws 56, integrally formed on the gears 57, are moved upwardly and downwardly, respectively, to closed gripping positions on one side or end of the bag hems 7', as best shown in Figure 7. It will thus be noted that the combined pusher and bag opening fingers 55 are first moved into gripping engagement with the bag hems 7', before the side hem gripping jaws 56 are moved to closed position, and the latter are thereafter actuated to grip the ends of the hems, without disturbing the closed fingers 55. In other words, the pusher and opening fingers 55 and the side hem gripping jaws 56 are moved independently of each other. This independent movement is effected through the medium of the novel arrangement of the pins 62 and clutch plates 65, carried by the finger sleeve portions 61 and rock shafts 40 and 42, respectively.

With the bag hems 7' gripped by the pusher and bag opening fingers 55 and the side hem gripper jaws 56, see Figure 7, the gripper and feed carriage 36 continues to move forwardly and the cam track is caused to move upwardly. As the cam track 75 is elevated, due to the action of the cam 53 on lever 76, the arm 72 is raised, in the direction of the arrow 102, Figure 11, and the top and bottom front rock shafts 40 and 42 are rocked in clockwise and counter-clockwise directions, respectively, through the gears 82-83. This movement of the rock shafts expands or spreads the pusher and bag opener fingers 55 apart so that the mouth of the bag is opened, 70 as illustrated in Figures 8 and 9. This opening or spreading movement of the pusher and gripping fingers 55 is effected by virtue of the frictional engagement of the pins 62, carried by the sleeves 61, sleeved on shafts 40 and 42, with the

5 side faces 66 of the clutch plates 65, carried by the rock shafts 40 and 42. Thus, as the bent outer ends 64, of pins 62, frictionally engage the clutch plates 65, the fingers 55 will be elevated or spread apart simultaneously, with the rocking movement of the shafts 40-42 and clutch plates 65, until the rearwardly extending pins 63, on finger collars 61, engage the flattened faces 106, of collars 105 fixed on the top and bottom rear rock shafts 41 and 43. When the pins 63 engage the collars 105, the pins 62 and the fingers 55 are prevented from rocking any further, whereby the rock shafts 40-42 and clutch plates 65 may continue to be rocked, without disturbing the open or expanded positions of the fingers 55, for a purpose presently to be described. Therefore, it will be understood that, the pusher and gripping fingers 55 are moved to the open or expanded positions, just described, without moving or otherwise disturbing the side hem gripping jaws 56, which remain in closed gripping engagement with the end of the bag hems 7'.

As the bag blank 7 is now spread open and clamped by the side hem grippers 56, see Figure 8, the gripper and feed carriage 36 is caused to move forwardly, in the direction of the arrow 103, Figure 11, due to the action of cam 53 on lever 48, and carries the opened and gripped bag over one pair of horizontally disposed bag holding arms, shown in Figures 1, 2, 8 and 9, of a series of four pairs of arms pivotally mounted in a rotating turret head, not shown. The bag arms 94 have previously been bent inwardly in opposed directions, in a manner described and illustrated in my pending application, Serial No. 250,223, filed January 10, 1939, to facilitate positioning of the bag thereon. When the gripper and feed carriage 36 reaches the end of its forward travel, with the bag blank 7 gripped, opened and completely disposed on the pair of bag holding arms 94, as shown in Figure 9, the bag holding arms 94 are expanded so as to engage the sides of the bag blank and to firmly retain the same in position thereon, in a manner not shown in this application. With the bag blank 7 mounted on and gripped by the holding arms 94, the cam track is elevated a relatively short distance, in the direction of arrow 104, Figure 11, which further lifts the arm 72 upwardly and continues to rock the top and bottom front rock shafts 40 and 42 in clockwise and counter-clockwise directions, respectively, through the gears 82-83. This further rocking movement of shafts 40 and 42 rotates the clutch plates 65 relative to the pins 62 and also rocks the U-shaped lug 68 downwardly, in a clockwise direction, and causes the upper pin 78 thereon to engage and rock the lug 71 and top rear rock shaft 41, in a corresponding clockwise direction, thereby moving the spring tensioned lug 68 forwardly out of engagement with the cam faced lug 67. The rocking movement of the lug 68 causes the spring 88, which has previously been placed under tension during the movement of the side hem grippers 56 to hem clamping position, to exert a pull upon and rotate the top segment gear 57 and gripper jaw 56 in a clockwise direction which in turns rocks the lower segment gear 57 and gripper jaw 56, in an opposing or counterclockwise direction. The bag blank 7, having been accurately and uniformly placed upon and clamped by the bag holding arms 94, is now released by the side hem grippers 56. It will be noted that this final opening movement of the side hem gripping jaws 56, to release the end of the bag hems 7', is effected

without moving or interfering with the open or expanded pushing and bag opening fingers 55. This, as previously explained, is accomplished by reason of the frictional engagement of the pins 62 and clutch plates 65 which permits of independent movement of the fingers 55 and jaws 56. Rotation of the cam 53 now swings the lever 48 rearwardly and moves the bag gripper and feeding carriage 36 rearwardly, in the direction of arrow 98, Figure 11, towards the forward end of feed or transfer plate 9, in position to receive another bag blank 7, that is, with the respective pushing and opening fingers 55 and side hem gripping jaws 56 in fully expanded open position.

Due to the fact that the bag pusher plate 15, extending into the top hem 26 of the hems 7', pushes the bag blank 7 forwardly to the end of the feed or transfer plate 9 and holds the bag in position until the feed carriage 36 reaches the end of its return stroke, the hems 7' of the bag are first properly and uniformly aligned before the combined pushing and gripping fingers 55 are moved into the hems 7'. Therefore the bag hems 7' are accurately and uniformly entered into and clamped by the fingers 55, which prevents of the bag blank 7, being misaligned while the fingers 55 are spreading open the mouth thereof and the side hem gripping jaws 56 are clamping the end of the hems 7'. The bag blank is pushed entirely on the pair of horizontally disposed bag holding arms 94, while the hems 7' are gripped by the fingers 55 and jaws 56, and the arms 94 are expanded to firmly retain the bag 7 thereon before the side hem gripping jaws 56 are opened to entirely release the bag. Thus, the bag hems 7' are uniformly and accurately adjusted on the lower ends of the arms 94 before being released by the gripper carriage 36. This is very important because it is essential that the edge of the bag hems 7', into which a pair of stringing needles, not shown, enter, be aligned with the needles, in order to prevent the needles from missing or otherwise failing to properly enter the hems of the bag, during the bag stringing.

While I have described and illustrated a preferred embodiment of my bag feeding and hem opening mechanism, it is to be understood that various changes and improvements may be made without departing from the scope and spirit of the appended claims.

Having thus described my invention, what I claim is:

1. In a machine of the character described having bag holding arms, a roll of hemmed bags, a substantially horizontally disposed bag feeding carriage for horizontally feeding hemmed bags from said roll to said bag holding arms, a series of horizontally disposed spaced shafts rotatably mounted on said carriage, a pair of normally open pushing and opening fingers loosely mounted on two of said shafts intermediate the ends thereof, and a pair of normally open gripping jaws on one end of said finger supporting shafts, meshing gears on said fingers and jaws for simultaneously moving said fingers and jaws to closed and open positions, means for reciprocating said carriage horizontally, and means for simultaneously rocking said shafts, means on said shafts engaging with means on said fingers whereby upon rocking of said shafts the fingers will be successively partially closed and aligned with the bag hems and upon forward travel of the carriage moved into and closed on said hems, without moving said jaws, closing said jaws on

one end of the hems, and opening said fingers for opening the mouth of the bag without moving said jaws during the forward travel of the carriage.

2. In a machine of the character described having bag holding arms, a support for a roll of hemmed bags, a substantially horizontally disposed bag feeding carriage for horizontally feeding hemmed bags from said roll to said bag holding arms, and pivotally mounted rotatable means associated with said support and engageable with said roll for rotating the latter to deliver bags to said feeding carriage, a series of horizontally disposed spaced shafts rotatably mounted in said carriage, a pair of forwardly extending normally open pushing and opening fingers sleeved on two of said shafts intermediate the ends thereof, and a pair of forwardly extending normally open gripping jaws carried at one end of said finger supporting shafts, reciprocating means engageable with and adapted to feed a bag between said fingers and jaws, cam means for reciprocating said carriage horizontally, means associated with said cam means for rotating said shafts in opposed directions and partially closing and aligning said fingers with said bag hems to adapt said fingers to enter thereinto on the forward travel of the carriage, means associated with said rotating means for closing said fingers on and clamping said hems and successively closing said jaws on one end of the hems, and opening said fingers for opening the mouth of the bag whereby said carriage feeds the opened and gripped bag onto said bag holding arms.

3. In a machine of the character described having bag holding arms, a support for a roll of hemmed bags, horizontal means for supporting a hemmed bag being fed from said roll, a substantially horizontally disposed bag feeding carriage for horizontally feeding hemmed bags forwardly from said supporting means to said bag holding arms, a series of horizontally disposed spaced shafts rotatably mounted in said carriage, a pair of forwardly extending normally open pushing and opening fingers sleeved on two of said shafts, and a pair of forwardly extending normally open gripping jaws carried by said finger supporting shafts, reciprocating means associated with said horizontal bag supporting means engageable with and adapted to feed a bag forwardly between said fingers and jaws, means for reciprocating said carriage horizontally relative to said horizontal bag supporting means, meshing gears on said shafts and means carried by one of said gears, and vertically movable means engageable with said gear means for actuating said gear means and for rotating said shafts in opposed directions and partially closing and aligning said fingers with said bag hems to adapt said fingers to enter thereinto on the forward travel of the carriage, means on said fingers engageable with means on said shafts for closing said fingers on and clamping said hems and successively closing said jaws on one end of the hems, opening said fingers for opening the mouth of the bag whereby said carriage feeds the opened and gripped bag onto said bag holding arms.

4. In a machine of the character described having bag holding arms, a support for a roll of hemmed bags, a relative flat horizontal plate for supporting a hemmed bag being fed from said roll, a substantially horizontally disposed bag feeding carriage associated with said plate for horizontally feeding hemmed bags forwardly

from said plate to the bag holding arms, a series of horizontally disposed spaced shafts rotatably mounted in said carriage, a pair of forwardly extending normally open pushing and opening fingers sleeved on two of said shafts, and a pair of forwardly extending normally open gripping jaws carried by said finger supporting shafts, reciprocating means associated with said plate engageable with the hem of and adapted to feed a bag forwardly between said fingers and jaws, means for reciprocating said carriage horizontally relative to said plate, meshing gears on said shafts, and a member carried by one of said gears, vertically movable means engageable with said member for actuating the latter and for rotating said shafts in opposed directions and partially closing and aligning said fingers with said bag hems to adapt said fingers to enter thereinto on the forward travel of the carriage, means on said fingers engageable with means on said shafts for moving said fingers with said shafts and closing the fingers on and clamping said hems, and successively closing said jaws on the hems, and opening said fingers for opening the mouth of the bag whereby said carriage feeds the opened and gripped bag onto said bag holding arms.

5. In a machine of the character described having bag holding arms, a support for a roll of hemmed bags, a relatively flat horizontal stationary plate for supporting a hemmed bag being fed from said roll, a substantially horizontally disposed bag being fed from said roll, a substantially horizontally disposed bag feeding carriage slidably mounted adjacent said plate for horizontally feeding hemmed bags forwardly from said plate to the bag holding arms, a series of horizontally disposed spaced rock shafts rotatably mounted in said carriage, a pair of forwardly extending normally open pushing and opening fingers sleeved on one pair of said shafts, and a pair of forwardly extending normally open gripping jaws carried by one end of said finger supporting shafts, reciprocating means associated with said plate engageable with the hem of and adapted to feed a bag forwardly along the plate between said fingers and jaws, means for reciprocating said carriage horizontally relative to said plate, a pair of gears on said finger supporting shafts and cam means associated with said gears for rocking said shafts in opposed directions and partially closing and aligning said fingers with said bag hems to adapt said fingers to enter thereinto on the forward travel of the carriage, means on said fingers frictionally engaging with means on said shafts for simultaneously rocking said fingers and shafts, and closing the fingers on and clamping the hems, and successively closing said jaws on the hems, and opening said fingers for opening the mouth of the bag whereby said carriage feeds the opened and gripped bag onto said bag holding arms.

6. In a machine of the character described having bag holding arms, a support for a roll of hemmed bags, a relatively flat horizontal stationary plate for supporting a hemmed bag being fed from said roll, a substantially horizontally disposed bag feeding carriage slidably mounted adjacent said plate for horizontally feeding hemmed bags forwardly from said plate to the bag holding arms, a series of horizontally disposed spaced rock shafts rotatably mounted in said carriage, a pair of forwardly extending normally open pushing and opening fingers sleeved on one pair of said shafts, and a pair of

forwardly extending normally open gripping jaws carried by one end of said finger supporting shafts, reciprocating means associated with said plate engageable with the hem of and adapted to feed a bag forwardly along the plate between said fingers and jaws, means for reciprocating said carriage horizontally relative to said plate, a pair of gears on said finger supporting shafts and cam means associated with said gears for 5 rocking said shafts in opposed directions and partially closing and aligning said fingers with said bag hems to adapt said fingers to enter thereinto on the forward travel of the carriage, a substantially vertical pin on each of said fingers frictionally engaging with a substantially vertical plate on each of said finger supporting shafts for simultaneously rocking said fingers and shafts for closing the fingers relative to said jaws and clamping the hems, and means on said shafts 10 engageable with said jaws for moving the jaws to closed clamping position relative to said closed fingers and clamping one end of the hems, and said fingers being moved to open position by the rocking of said shafts for opening the mouth of the bag whereby said carriage feeds the opened and gripped bag onto said bag holding arms.

7. In a machine of the character described having bag holding arms, a support for a roll of hemmed bags, a relatively flat horizontal stationary plate for supporting a hemmed bag being fed from said roll, a substantially horizontally disposed bag feeding carriage slidably mounted adjacent said plate for horizontally feeding hemmed bags forwardly from said plate to the bag holding arms, a series of horizontally disposed spaced rock shafts rotatably mounted in said carriage, a pair of forwardly extending normally open pushing and opening fingers sleeved on one pair of said shafts, and a pair of forwardly extending normally open gripping jaws carried by one end of said finger supporting shafts, reciprocating means associated with said plate engageable with the hem of and adapted to feed a bag forwardly along the plate between said fingers and jaws, means for reciprocating said carriage horizontally relative to said plate, a pair of gears on said finger supporting shafts and cam means associated with said gears for 15 rocking said shafts in opposed directions and partially closing and aligning said fingers with said bag hems to adapt said fingers to enter thereinto on the forward travel of the carriage, an upstanding pin on each of said fingers frictionally engaging with a relatively flat upstanding clutch plate carried by each of said finger supporting shafts for simultaneously rocking said fingers and shafts for moving the fingers to closed position relative to said open jaws and clamping the hems, and pin members on two of 20 said shafts for rocking said shafts simultaneously, and means on one of said shafts engageable with means secured to one of said gripping jaws for moving the jaws to closed position relative to said closed fingers and clamping one end of the hems, and said fingers being moved to open position relative to said closed jaws by said cam means for opening the mouth of the bag whereby said carriage feeds the opened and gripped bag onto said bag holding arms.

8. In a machine of the character described having bag holding means, a source of hemmed bag supply, a bag feeding carriage for feeding hemmed bags to said bag holding means, a series 25 of shafts rotatably mounted in said carriage, a

pair of normally open pushing and opening fingers sleeved on one pair of said shafts for extending into and engaging beneath the hems of the bag, and a pair of normally open gripping jaws mounted on one end of said finger supporting shafts for gripping one end of the bag hems, means for feeding a bag between said fingers and jaws, means for moving said carriage, a vertically movable lever mounted adjacent said carriage, and cam means for moving said lever vertically, a longitudinal guide slot in the upper end of said lever, and an arm carried by one of said shafts interengageable with and movable within said guide slot whereby during the movement of said feeding carriage said finger supporting shafts are rocked to successively partially close and move said fingers into the bag hems, close said jaws on one end of said hems, and to open said fingers for opening the mouth of the bag to permit of the opened and gripped bag being fed onto the bag holding means.

9. In a machine of the character described having bag holding means, a source of hemmed bag supply, a bag feeding carriage for feeding hemmed bags to said bag holding means, a series of shafts rotatably mounted in said carriage, a pair of normally open pushing and opening fingers sleeved on one pair of said shafts for extending into engagement beneath the hems of the bag, and a pair of normally open gripping jaws mounted on one end of said finger supporting shafts for gripping one end of the bag hems, means for feeding a bag between said fingers and jaws, means for moving said carriage, a vertically movable lever mounted adjacent the forward end of said carriage and cam means connected to the lower end of said lever for moving the same vertically, a guide track on the upper end of said lever having a longitudinal guide slot therein, and a forwardly extending arm carried by one of said shafts positioned and movable within said guide slot whereby during the movement of said feeding carriage said finger supporting shafts are rocked to successively partially close and move said fingers into the bag hems, close said jaws on one end of said hems, and to open said fingers for opening the mouth

of the bag to permit of the opened and gripped bag being fed onto the bag holding means.

10. In a machine of the character described having bag holding means, a support for a roll of hemmed bags, a bag feeding carriage for feeding hemmed bags to said bag holding means, and means engageable with and rotating said roll for delivering bags to said feeding carriage, and means for regulating the rate of delivery of bags from said roll to said carriage, a series of shafts rotatably mounted in said carriage, a pair of normally open pushing and opening fingers mounted on one pair of said shafts for extending into and engaging beneath the hems of the bags, and a pair of normally open gripping jaws on said finger supporting shafts for gripping one end of the bag hems, means for feeding a bag between said fingers and jaws, means for moving said carriage, and means for successively partially closing and moving said fingers into said bag hems during the movement of the carriages and closing said fingers on said hems independent of said jaws, and means for closing said jaws on one end of said hems without moving said closed fingers, and means for opening said fingers without disturbing said closed gripping jaws for opening the mouth of the bag whereby said carriage feeds the opened and gripped bag onto said bag holding means.
11. In a machine of the character described having bag holding means, a source of hemmed bag supply, a substantially horizontal bag supporting plate, a bag feeding carriage movably mounted on said plate and having pushing and opening means thereon engaging with the hems of and for feeding hemmed bags to said bag holding means, a guide slot adjacent said plate having a block slidably mounted therein, a forwardly extending tongue member carried by said block and adapted to be moved over said supporting plate for entering the hem of and pushing a bag forwardly on said plate into position to be engaged by said feeding carriage, and means for moving said carriage on said plate relative to said tongue member for feeding a bag onto said bag holding means.

EDWARD E. WEST.
